TREATMENT OF HYDROCARBON OILS

Gustav Egloff, Chicago, Ill., assignor to Universal
Oil Products Company, Chicago, Ill., a corpora-
tion of South Dakota

Application May 14, 1931, Serial No. 537,258

7 Claims. (Cl. 196—60)

This invention relates to the treatment of hydrocarbon oils and refers particularly to the conversion of hydrocarbon oils into oils of more desirable characteristics.

5 The primary concepts of the present invention comprise separating the relatively light and relatively heavy components of crude petroleum, thence subjecting each of the separate components to independently controlled conversion 10 conditions for the production of substantial quantities of more desirable products such as motor fuel of high anti-knock value.

In its more specific embodiment, the invention 15 may comprise subjecting a crude oil, of the type which contains a substantial proportion of relatively light components such as gasoline or other low boiling distillates, to substantial vaporization, subjecting the vapors to fractionation to effect separation and recovery of said relatively light 20 components, collecting the unvaporized oil, together with reflux condensate from said fractionation, and subjecting this oil, which comprises relatively heavy components of the crude, to conversion conditions in the heating element, preferably under a substantial superatmospheric pressure, introducing the heated products into a reaction zone, withdrawing both vaporous and liquid 25 products from said reaction zone to a vaporizing zone preferably maintained under substantially reduced pressure and wherein vaporous products 30 may separate from the residual products of conversion, subjecting the vaporous reaction products to fractionation, returning the relatively heavy insufficiently converted components of the 35 vapors which may be condensed in said fractionating zone to further conversion in said heating element, subjecting the vapors and gases from said fractionator to condensation and cooling and collecting the resulting products, simultaneously 40 subjecting the relatively light components of the crude oil separated from the relatively heavy components, as already described, to independently controlled conversion conditions in a separate heating element and introducing the heated products into the aforementioned reaction zone to be 45 subjected therein and in subsequently subjecting portions of the system to the same treatment as that afforded the heated products from the first mentioned heating element.

50 As a feature of the invention, a portion or all of the heat required for effecting substantial vaporization of the crude oil to permit separation of its lighter from its heavier components may be recovered from the relatively hot vapors and gases

and/or liquids within the cracking system by indirect heat exchange therewith.

The process of the present invention is best adapted to the treatment of crude oils which contain a substantial proportion of gasoline of 5 inferior quality, especially with respect to its anti-knock rating, as, by the provisions of the present invention, this inferior motor fuel may be separated from the heavier portions of the crude and thence subjected to conditions, preferably of relatively high temperature and substantial super-atmospheric pressure, under which it will be reformed or its characteristics will be so altered that the product is a motor fuel possessing 10 high anti-knock value as well as other desirable characteristics.

The present invention possesses the economic advantage of effecting the reconversion or altering the undesirable properties of the gasoline and/or other relatively light components of a 20 crude oil simultaneously with and in a portion of the same apparatus in which the relatively heavy components of said crude oil are converted into more desirable light products, accomplishing the temperature treatment of each of the two 25 components of the crude under independently controlled conditions which give the most desirable results from each oil.

The attached diagrammatic drawing illustrates 30 one form of apparatus which embodies the principles of the present invention and the following description of the drawing embraces a description of the process of the invention as it may be practiced in the apparatus illustrated. A crude oil, preferably containing a substantial proportion of relatively light components, such as motor fuel of inferior quality, may be supplied through line 1 and valve 2 to pump 3 from which it may be fed through line 4, valve 5, heat exchanger 6, line 7, valve 8, heat exchanger 9, line 10, valve 11, heat exchanger 12, line 13 and valve 14 into top- 35 ping and fractionating column 15. Heat exchanger 6 may be located within the path of vapors passing from the vaporizing zone to the fractionating zone of the cracking system. Heat 40 exchanger 9 may be located in the path of liquid and vaporous products passing from the reaction chamber to the vaporizing zone. Heat exchanger 12 may be located within the path of heated oil passing from the secondary heating element to 45 the reaction chamber of the cracking system. The crude oil may be heated in a heat exchanger by indirect contact with the relatively hot products within the cracking system. It will be understood that heat exchangers located elsewhere 50

in the system or other means of supplying heat to the crude oil may be employed, if desired. It will also be understood that any or all of the heat exchangers mentioned may be by-passed, if so desired, by well known means, not illustrated in the drawing.

Topping and fractionating column 15 may be maintained under substantially atmospheric or under a substantial super-atmospheric pressure, 10 or, if desired, subatmospheric pressures may be employed in this zone. The crude oil may be heated under substantially the same or under a higher pressure than that employed in column 15 and the temperature attained by the crude, 15 prior to its introduction to this column, is sufficient to effect vaporization of a substantial portion of the oil under the conditions maintained in column 15. The portion vaporized includes substantially all of the light components of the 20 crude which it is desired to separate from the heavier components. Fractionation of the vapors and separation of said relatively light components therefrom may be effected by any suitable fractionating means such as bubble trays, 25 perforated pans, packing or the like in column 15.

The relatively heavy components of the crude oil, including those remaining unvaporized in column 15 and the reflux condensate condensed from 30 the vapors in this zone, may be withdrawn from the lower portion thereof through line 16 and valve 17 to pump 18 from which they may be fed through line 19, valve 20 and line 21 to heating element 22.

Heating element 22 may be located within any suitable form of furnace 23, capable of supplying the required heat to the oil undergoing treatment in the heating element. The oil is heated in this zone to the desired conversion 40 temperature preferably under a substantial super-atmospheric pressure and may be discharged from the heating element through line 24, valve 25 and line 26 into reaction chamber 27. Chamber 27 is also preferably maintained under a substantial super-atmospheric pressure which may 45 be substantially equalized with or lower than that employed in the heating element. Both liquid and vaporous products may be simultaneously discharged from chamber 27 through line 28, 50 valve 29, heat exchanger 9 and line 30 into vaporizing chamber 31 which is preferably maintained under a substantially reduced pressure relative to that employed in chamber 27.

The vaporous products may separate from the 55 residual products of conversion in chamber 31. In case the residual material produced is a liquid it may be withdrawn from chamber 31 through line 32 and valve 33 to storage or to any desired further treatment, however, if so desired, conditions may be so regulated in chamber 31 that a substantially dry carbonaceous residual product will result, in which case it may be allowed to accumulate within the chamber to be removed after the operation of the process is discontinued. 60 Or, if desired, a plurality of chambers similar to chamber 31, but not illustrated in the drawing, may be employed and may be operated either alternately or simultaneously to prolong the operating cycle.

Vapors and gases may be withdrawn from 70 chamber 31 through line 34, valve 35, heat exchanger 6 and line 36 to fractionation in fractionator 37. The relatively heavy insufficiently converted components of the vapors may be condensed within the fractionator collecting within

the lower portion thereof from which they may be withdrawn through line 38 and valve 39 to pump 40, by means of which they may be fed through line 21 and valve 41 to heating element 22 for further conversion, together with the 5 topped crude from column 15. Fractionated vapors and gases may pass from fractionator 37 through line 42 and valve 43, may be subjected to condensation and cooling in condenser 44, products from which may pass through line 45 10 and valve 46 to be collected in receiver 47. Uncondensable gas may be released from receiver 47 through line 48 and valve 49. Distillate may be withdrawn from the receiver through line 50 and valve 51. A portion of the distillate from 15 receiver 47 may, if desired, be recirculated by well known means, not illustrated in the drawing, to the upper portion of fractionator 37 to assist fractionation of the vapors in this zone.

The relatively light components of the crude 20 oil which are separated from its heavier components in column 15 may be separated in this same zone into a relatively light distillate and uncondensable gas. The distillate, which preferably comprises substantially all of the naturally 25 contained gasoline in the crude, may collect upon a tray or deck, not shown, in the upper portion of column 15 to be withdrawn therefrom through line 70 and valve 52 to pump 53 by means of which it may be supplied through line 54 and 30 valve 55 to heating element 56. The uncondensable gas, withdrawn from column 15 above the point from which the gasoline or relatively light distillate is withdrawn, may pass through line 57 and valve 58 to pump 59, which may function as 35 a vacuum pump in case subatmospheric pressure is maintained in column 15. The uncondensable gas may be passed from pump 59 through line 60 and may be discharged, all or in part, from the system to storage or elsewhere 40 through line 61 and valve 62 or may be discharged, all or in part, from line 60 through line 63 and valve 64 into line 54 and thence to heating element 56, together with the distillate withdrawn from column 15. 45

Heating element 56 may be located within any suitable furnace 65 and the distillate or distillate and gas supplied thereto may be heated to the desired temperature under any desired pressure conditions and preferably under a substantial 50 super-atmospheric pressure. The heated materials may be discharged from heating element 56 through line 66, valve 67, heat exchanger 12, line 68 and valve 69 into line 26 commingling 55 therein with the heated oil discharged from heating element 22 and passing therewith to reaction chamber 27 to undergo, in this chamber and in subsequent portions of the system, the same treatment, as already described, to which said heated oil from heating element 22 is subjected. 60

Pressures employed within the system may range from sub-atmospheric to super-atmospheric pressures as high as 2000 pounds or more per square inch. Conversion conditions employed may range from 800 to 1200° F., more or less. 65 Preferably, the topped crude and reflux condensate is subjected in the heating element in which they are treated to temperatures of the order of 850 to 950° F., and superatmospheric pressures which may range from 100 to 500 pounds per 70 square inch, more or less. Preferably reduced pressures of the order of substantially atmospheric to 100 pounds per square inch or thereabouts are employed in the vaporizing, fractionating, condensing and collecting portions of the 75

cracking system. Pressures employed in the topping and fractionating column may range from sub-atmospheric to 100 pounds or more super-atmospheric pressure per square inch. The relatively light components of the crude may be subjected in the heating element in which they are treated to temperatures of the order of 900 to 1200° F., more or less, under pressure conditions which may range from sub-atmospheric to 500 pounds per square inch, or more super-atmospheric pressure.

As an example of one of the many operations which may be practiced in the process of the present invention, a Pennsylvania crude oil containing approximately 37% of gasoline is the raw oil charging stock supplied to the process. Substantially all of the gasoline is separated from the crude in the topping and fractionating column and after subjection to a temperature of approximately 940° F. under a pressure of approximately 400 pounds per square inch is introduced into the reaction chamber of the cracking system together with the topped crude which is previously subjected, together with the reflux condensate from the cracking system, to a temperature of about 900° F. under a super-atmospheric pressure of approximately 350 pounds per square inch. A pressure of about 350 pounds per square inch is maintained in the reaction chamber but is reduced in the vaporizing, fractionating, condensing and collecting portions of the system to a substantially equalized pressure of about 50 pounds per square inch. This operation may yield approximately 72% of motor fuel based on the crude oil charged to the system. This motor fuel may have an octane number of about 83 as compared with an octane number of about 20 for the straight run gasoline obtained from the crude before it is reformed. In addition, to the motor fuel about 18% of heavy residual oil and a relatively small percentage of coke or carbonaceous material are produced, the only other product of the system being a rich undensable gas.

I claim as my invention:

1. A process of hydrocarbon oil conversion, which comprises subjecting a crude oil containing gasoline to a distillation temperature sufficient to vaporize the gasoline, separating the gasoline from the topped crude and subjecting same to vapor phase cracking conditions, simultaneously subjecting the topped crude to liquid phase cracking conditions of temperature and superatmospheric pressure in a separate zone, merging the highly heated vapors from the vapor phase cracking zone with the heated topped crude issuing from the liquid phase cracking zone, discharging said mixture into an enlarged reaction zone where separation takes place between vapors and non-vaporous residue, subjecting the vapors to fractionation to condense the heavier fractions thereof as reflux condensate, returning regulated portions of the reflux condensate to the liquid phase cracking zone for retreatment, removing the vapors remaining uncondensed after fractionation and condensing and collecting same as a distillate product of the process.

2. A process such as claimed in claim 1, characterized in that the gasoline passing through the vapor phase cracking zone is subjected to higher temperature conditions than the topped crude passing through the liquid phase cracking zone.

3. A process such as claimed in claim 1, char-

acterized in that the crude including gasoline is raised to distillation temperature by indirect heat exchange with the products issuing from the vapor phase and liquid phase cracking zones.

4. A process such as claimed in claim 1, characterized in that the conditions of vapor phase cracking are controlled to substantially increase the anti-knock characteristics of the gasoline subjected to vapor phase cracking.

5. A process of hydrocarbon oil conversion, which comprises subjecting a crude oil containing gasoline to a distillation temperature sufficient to vaporize the gasoline, separating the gasoline from the topped crude and subjecting same to vapor phase cracking conditions, simultaneously subjecting the topped crude to liquid phase cracking conditions of temperature and superatmospheric pressure in a separate zone, merging the highly heated vapors from the vapor phase cracking zone with the heated topped crude issuing from the liquid phase cracking zone, discharging said mixture into an enlarged reaction zone where separation takes place between vapors and non-vaporous residue, subjecting the vapors to fractionation to condense the heavier fractions thereof as reflux condensate, returning regulated portions of the reflux condensate to the liquid phase cracking zone for retreatment, removing the vapors remaining uncondensed after fractionation and condensing and collecting same as a distillate product of the process.

6. A process of hydrocarbon oil conversion which comprises subjecting a crude oil containing gasoline to distillation temperature sufficient to vaporize the gasoline and separating the gasoline from the crude, passing portions of the crude heavier than gasoline through a heating zone and heating the same therein to cracking temperature under sufficient pressure to maintain a substantial portion thereof in liquid phase, simultaneously subjecting gasoline boiling hydrocarbons separated from the crude, while substantially in vapor phase, to higher cracking temperature than the oil in said heating zone and then commingling the same with the heated products discharged from said heating zone, separating the commingled oils in an enlarged separating zone into vapors and residue, fractionating the separated vapors to condense heavier fractions thereof, and finally condensing and collecting the vapors uncondensed by the fractionation.

7. A process of hydrocarbon oil conversion which comprises subjecting a crude oil containing gasoline to distillation temperature sufficient to vaporize the gasoline and separating the gasoline from the crude, passing portions of the crude heavier than gasoline through a heating zone and heating the same therein to cracking temperature under pressure, simultaneously passing gasoline boiling hydrocarbons separated from the crude through a second heating zone maintained at higher cracking temperature than the first-named heating zone and heating the same therein sufficiently to enhance the anti-knock value thereof, commingling the heated products from

55 said heating zones and separating the same in an enlarged separating zone into vapors and residue, and fractionating and condensing the separated vapors.
